LUIGI PAVIA, OF ALLENTOWN, PENNSYLVANIA.

SHUTTLE.

Application filed August 6, 1927. Serial No. 211,207.

In shuttles of the type in which the spindle, pivoted therein, is split from the butt toward the point and there are a spring means in the split normally acting to expand the split portion and means in the shuttle body to cause collapse of the split portion of the spindle when the latter is raised on its pivot and allow the weft package to be slipped on or off the spindle said spring means has heretofore been arranged to act only on the butt-end part of the spindle, or substantially coincident with its pivot. It is found in practice that in this construction the spindle does not always effectually hold the package against lengthwise slippage because the spreading of the legs to grip the bore of the weft package is confined to their butt-end portions, so that the package is only locally gripped—
at its butt-end. The principal object of this invention is to extend the gripping action of the spindle with respect to the package toward the point of the spindle, thus not only more to effectually grip a package nicely adapted to the spindle but in fact obtain an effectual grip on packages whose bores are perhaps larger and hence not so nicely adapted to the spindle. A further object is to obtain this result by resort to simple means requiring simple operations in the forming of the spindle and assembling of its parts.

In the drawing,

Fig. 1 is a plan view of a shuttle;

Fig. 2 is a transverse section on line 2—2 of Fig. 1;

Fig. 3 is an inside elevation of one leg of the spindle and the spring which maintains the spindle in either the depressed (or closed) or elevated (or open) position, with certain pins shown in section;

Fig. 4 is a longitudinal section of the spindle in a plane bisecting both legs thereof; and

Fig. 5 is a view similar to Fig. 4 but showing a modification.

The shuttle body 1, having the usual cavity 2 for the weft package and the extension cavity 3 communicating with cavity 2; the transverse pin 4 traversing the cavity 3 serving as a pivot for the spindle; the converging fixed plates 1^a for causing collapse of the spindle when the same is raised by assuming the wiping action of its converging lateral butt-faces; and the pins 5 serving to support the usual bent spring 6 for holding

the spindle either depressed or elevated in contact with the pin 7, are or may be all substantially of a well-known construction.

The spindle also may follow a well-known construction in so far as it comprises two longitudinal substantially counterpart sections or halves 8 which at the free ends thereof may be welded or otherwise secured together to form a unitary body but from a point near said free ends are unconnected so that from such point toward the butt the spindle is in effect split; and in accordance with such well-known construction it may have in said sections and at the butt thereof the aligned holes 9 to receive the spiral spring 11 which when the parts are assembled as in Fig. 1 and when the spindle is depressed or closed normally acts to spread or expand the split part of the spindle. There may also be flutings 12 or equivalent on the spindle to grip the bore of the weft package.

According to this invention, before the halves or sections of the spindle are assembled they are formed with inside longitudinal grooves 13 which will be opposite each other when said sections are assembled. These grooves receive an elongated arched spring 14 consisting of a piece of tempered metal having a suitable curvature therein and preferably having its ends slightly bent. This spring may be assembled with the spindle as shown in the drawing after the sections of the spindle have been welded or otherwise secured together as described.

In Fig. 5 the construction is substantially the same as already described excepting that one of the grooves 13 has a recess 15 therein and one end of the spring 14' is bent off and engaged in said recess; if desired this recess may be a hole through which the end of the spring protrudes and such protruding end may be upset or riveted, as at 16. This construction insures against the spring working endwise in the grooves and possibly escaping from the shuttle to cause damage to the goods being woven.

Having thus fully described my invention, what I claim is:

1. The combination of a shuttle body having a weft-package cavity and a spindle pivoted in said body on an axis traversing the cavity, said spindle being split from near its free end to its other end and thus having legs, means near the spindle pivot to spread

apart said legs when the spindle is depressed, said body having means to press said legs together when the spindle is raised, and a spring interposed between the legs at a point between said means and the free end of the spindle and also active to spread apart said legs when the spindle is depressed.

2. The combination of a shuttle body having a weft-package cavity and a spindle pivoted in said body on an axis traversing the cavity, said spindle being split from near its free end to its other end and thus having legs and having a longitudinal groove in one leg facing the other leg, said body having means to press said legs together when the spindle is raised, and an elongated spring interposed between the legs and seated in

said groove and active to spread said legs apart when the spindle is depressed.

3. The combination of a shuttle body having a weft-package cavity and a spindle pivoted in said body on an axis traversing the cavity, said spindle being split from near its free end to its other end and thus having legs and having a longitudinal groove in each leg facing the other leg, said body having means to press said legs together when the spindle is raised, and an elongated spring interposed between the legs and seated in both grooves and active to spread said legs apart when the spindle is depressed.

In testimony whereof I affix my signature.

LUGI PAVIA.
